US0D1098832S

(12) **United States Design Patent** (10) **Patent No.:** **US D1,098,832 S**
(45) **Date of Patent:** **** Oct. 21, 2025**

(54) **TUMBLER**

(71) Applicant: **LOUIS VUITTON MALLETIER**,
Paris (FR)

(72) Inventors: **Pierre Hulot**, Paris (FR); **Julia
Maendler**, Paris (FR)

(73) Assignee: **Louis Vuitton Malletier**, Paris (FR)

(**) Term: **15 Years**

(21) Appl. No.: **29/887,536**

(22) Filed: **Mar. 22, 2023**

(30) **Foreign Application Priority Data**

Sep. 23, 2022 (FR) 20223845
